UNITED STATES PATENT OFFICE.

HENRY W. MASON, OF SOUTH COVENTRY, CONNECTICUT.

CARTRIDGE-MACHINE.

SPECIFICATION forming part of Letters Patent No. 253,213, dated February 7, 1882.

Application filed March 19, 1881. (No model.)

To all whom it may concern:

Be it known that I, HENRY W. MASON, a citizen of the United States, residing at South Coventry, county of Tolland, and State of Connecticut, have invented a new and useful Improvement in Machines for Making Cartridges, of which the following is a specification.

My invention relates to that class of machines known as "cartridge-loading" machines, and specially to that description of such machines for the manufacture of blank cartridges, or that description of cartridges requiring a wad to be placed over the powder contained within the cartridge-shell for securely holding the powder therein.

Machines for the manufacture of such described cartridges heretofore have been so constructed as to require the wad to be cut by a separate and distinctive machine or device, and then supplied by an additional device to the punch for setting the wad into the shell.

My improvement consists in arranging such machines so that the cutting of the wad and the placing or setting of it into the shell are performed by one punch and by one movement of the said punch, which performs the functions of cutting the wad and setting it into the shell in the required position at the same instant of time. I attain these objects by the mechanism illustrated in the accompanying drawings, in which—

Figure 1 is a top view of the entire machine; Fig. 2, a face or front view of that part of the frame in which is set the vertically-reciprocating head carrying the several punches; Fig. 3, a vertical section of Fig. 2; Fig. 4, a top view of a section of the machine.

Similar letters refer to similar parts throughout the several views.

A is the powder-pressing punch; B, the wad-cutting and wad-setting punch; C, the crimping or swaging punch; D, the clearing or discharging punch; P, the frame, in which is set the punch-carrier; Q, the reciprocating head; R, the plate for holding the wad-strip in position while the cutting-punch ascends; S, the strip from which the wads are cut; T, the powder-magazine; I, the bottom opening in the magazine; H, the powder-charging plate; J, the opening through the charging-plate to receive and deliver the powder in the shell; K,

the cartridge-shell supply or feed plate; L, the guide; M, the carrier-plate; O, the openings in carrier-plate; N, the ratchet-plate; E E, the feeding-rollers; G, the die; W, the set-screw 55 for die G; F, the punch-adjusting nuts.

The construction and functions of the different parts of the machine, with the exception of my improvements, which new devices or improvements are designated in the several views 60 by the letters B, G, R, E E, and S, are old and well-known devices, and form no part of my invention, excepting so far as the combination of my new devices therewith, and therefore require no description.

The construction, operation, and functions of the several devices constituting my improvement are as follows, viz: The feed-rollers E E are placed in the position as shown in Fig. 3, and an intermittent rotary motion given to 70 them by a ratchet device moved by a reciprocating lever or pawl. The die G, with a cylindrical opening made clear through it, is fixed to a lower portion of the frame and held in position by the set-screw W. The face of 75 this die is on a plane, or nearly so, with the nearly-conjoined peripheries of the feed-rollers. The plate R, fixed to the frame, as shown in Fig. 3, by a screw, projects over the face of the die G. Through this plate R is made a cylindrical opening coincident with the cylindrical opening forming the die G. The strip S is formed out of any proper material, and of a length and width as desired.

The operation and functions of my new devices are as follows, viz: The machine having been set in motion and the shells charged with powder and conveyed to the punches in the usual and well-known manner pass under the punches and the die G. At the same time the 85 feed-rollers E E, having an intermittent rotary motion, carry forward the wad-strip S, passing it over the face of the die G and beneath the plate R the required distance, and while the carrying-plates are at rest the punch B (or cutting-die punch) descends, passing through the opening made in the holding-plate R, takes upon the strip of material S, cuts out a wad, forces it down through the opening in the die 90 G, and sets and ramms it into the shell, which 95 has been previously charged with powder, rammed by the punch A, and carried under 100

the die G, ready to receive the wad. The cartridge thus far finished is, by another movement of the machine, carried under the punch C, (which at its lower end is made of a con-
5 cave shape,) that crimps or swages the shell at its top over the wad, as required. Another movement carries the completed cartridge under the clearing-punch, and it is by it thrown out finished. The machine is automatic in ac-
10 tion, and the pressing, wad cutting and setting, crimping, and discharging punches are simultaneous in action, operated by one and the same movement of the reciprocating head, to which they are fixed. The wad-strip S, in
15 passing under the cutting-punch B, is cut in a successive single line of holes its entire length at one side, and then, with its edges reversed, passed again through the rollers, and wads cut out as in its first passage, as shown in Fig. 4.
20 It is obvious that several modifications of the devices shown may be made, (but that in no manner would differ in principle,) viz:

The magazine may be made to charge two of the openings J of the powder-charging plate
25 H and a double set of punches, A B C D, and die G, arranged beside each other, thus pro-
lucing double the number of cartridges in the same time.

The strip S, instead of being in short lengths,
30 may be made in coils and taken from a reel by action of the feed-rollers. The lower feed-roller
could also be dispensed with, and the peripher-
ery of the upper roller being milled or serrated,
and the wad-strip resting upon a smooth steel
35 surface, would be drawn forward by pressure
of the roller; or both rollers may be dispensed

with, and in lieu of them a reciprocating lever
or pawl, arranged to push forward the wad-
strip S; but I prefer the machine made as de-
scribed, and shown in the drawings.

The greater space shown between the punches
A and B than between B, C, and D is for the
purpose of another punch, made conical at its
lower portion, being placed therein to spread
45 the mouth of the shells when they may be to
any extent contracted; but such punch is sel-
dom required, and never for small cartridge-
shells.

What I claim as my invention, and desire
to secure by Letters Patent, is—
50

1. In a cartridge-loading machine, the com-
bination, with the shell-carrying mechanism,
of the rammer A, the wad cutter and setter,
having feed-rolls E E to supply the wad ma-
terial thereto, and holding-down plate R, as
55 described, and the swaging-punch C, operat-
ing together as set forth.

2. The combination, with the shell-convey-
ing mechanism, of the rammer A, the wad cut-
ting and setting mechanism, substantially as
60 described, and the swaging or closing punch
C, substantially as set forth.

3. In combination with the shell-conveyer,
the wad cutting and setting punch and mech-
anism for supplying the wad material thereto,
65 substantially as described, and the swaging or
closing punch, all substantially as set forth.

HENRY W. MASON.
